UNITED STATES PATENT OFFICE

1,927,291

LOCOMOTIVE REFILLING SYSTEM

Frank W. Miller, Chicago, Ill.

Application January 17, 1929. Serial No. 333,231

5 Claims. (Cl. 122—396)

This invention pertains to the refilling of locomotive boilers at locomotive terminals. It successfully deals with the several problems that must be met because of the use of impure water in the boilers and furthermore makes available some new advantages in the operation of locomotive terminal equipment.

Whether or not water softening materials are added to the boiler water it is necessary to empty and wash out the locomotive boilers frequently, and when water softening materials are added they create the additional problem of disposing of large quantities of sludge precipitated in the water when boiled. Heretofore it has been common practice, and still is, to refill the boilers with cold water or water at about 120° to 130° F. and create steam thereafter in each boiler by a fire built on its own grate. In either case an hour to an hour and one-half has been necessary to create enough steam for the working operation of the locomotive and enormous clouds of smoke and fumes are emitted from the terminal using these methods. Not only do such methods create a serious smoke nuisance and needlessly delay the use of costly locomotives, but the locomotives thus put into service are already loaded with large accumulations of sludge.

It has been suggested that live steam should be injected either with the cold or warm water entering the boilers or subsequently, but such a use of steam would be a too enormous and sudden load upon the power house boiler equipment generally available and even then would not prevent the boilers from going into service well loaded with sludge.

In utilizing this invention a locomotive boiler is filled with water at such a high temperature that when the normal water level is attained it will have adequate steam pressure therein for moving out of the round house under its own power without using fire in its fire box. Furthermore, this refilling operation can be accomplished in about fifteen minutes very easily, as contrasted to the hour and one-half period formerly required for creating a working pressure in a locomotive by means of its own fire. When refilled in accordance with the methods herein outlined, the boiler will contain almost no sludge.

The use of this apparatus requires a considerable amount of high pressure steam to be supplied from the power house boiler and accordingly provision is made, as an object of the invention, to enable the refilling apparatus to assist the boiler in supplying sudden and continued demands for steam.

Another object of this invention is to provide means for refilling locomotive boilers quickly with superheated water to create working pressures in the refilled boilers and means for maintaining the working pressures in the boilers by direct injection of steam without serious loss of pressure in the system which supplies the steam.

Another object of this invention is to provide reliable and economical equipment having sufficient capacity for simultaneously and/or consecutively filling a large number of locomotive boilers with hot water under pressure and adapted to create working steam pressures in the boilers when refilled, the apparatus being adapted to operate efficiently under wide variations of load yet requiring only a relatively small amount of power house boiler capacity.

Other objects, advantages and capabilities of the invention are inherently possessed by it and will later become apparent.

Referring now to the drawing which schematically discloses the equipment, there are provided three mains which serve the various locomotive stalls in a round house, shown and labeled as follows, the blow-off main 1, the refill main 2 and the live steam main 3. The wash-out main which is ordinarily provided and would also be used with this equipment is not involved in the disclosure of this invention and is therefore not shown.

When a locomotive is being blown-off usually a flexible hose 4 is connected to its blow-off cock. This hose will preferably be connected to a box 5 which in turn is connected to the several drops provided at each stall. The water and steam which is being blown-off from the locomotive passes through the valve 6 which would at that time be the only valve open among the drops and flows through the blow-off main 1 to a separator 7. This separator may be of common construction and is adapted by centrifugal force to separate the steam from the water, allowing the water to flow down to the discharge pipe 8 to any suitable discharge receptacle or otherwise as may be desired, while the steam rises through the pipe 9 to a condenser 11. In the condenser this blow-off steam is caused to mingle with water forced by the pump 12 from the refill tank 13 through the pipes 14 into the condenser and thence back into the refill tank through the pipe 15. In practice this refill tank will ordinarily be kept full of water having a temperature of about 180° F. or more, which temperature is maintained by the frequent addition of blown-off steam in the condenser 11. Whenever additional

fresh water is required to maintain the level in the refill tank this may be supplied from a cold water main 16. The addition of the cold water may be controlled by any suitable water level 5 regulator such for example as the regulator 17 diagrammatically shown on the refill tank.

The water in the refill tank having a temperature of about 180° F., or more, is drawn by a pump 18 through the pipe 19 from the refill 10 tank and pumped through a pipe 21 into the first storage tank 22. The pump 18 is controlled by a pump governor 23 connected to the storage tank 22 by means of a pipe 24. This governor will start the pump whenever the pressure in the 15 tank 22 falls below a certain minimum pressure which may be anywhere from 100 to 150 pounds as may be desired by any given operator. When the governor opens live steam is admitted by the 20 governor through the pipe 25 to the pump 18 and starts the pump.

When this pump is operating and pumping refill 25 water into the bottom of the storage tank 22, normally it will force water from the top of the tank 22, which is always kept full, through the pipe 26 into the storage tank 27. Simultaneously with the starting of the pump, water will be forced from the top of the storage tank 27 out through the pipe 28 into the refill main 2. The refill main then 30 carries the water around to the various locomotive stalls.

In order that the refill water may be heated to a temperature of about 300° to 350° F. and this 35 temperature maintained continuously in the refill main, the end of the refill main is connected to a return line 29 which carries this water to a return 40 circulating pump 31. This pump will then cause the water to flow through the pipe 32 to either or both of the live steam heaters 33 and 34.

The live steam heaters 33 and 34 are shown 45 diagrammatically, each having a steam inlet pipe 35 and 36, respectively, and a steam coil 37 and 38, respectively. The water entering these live 50 steam heaters from the return line 32 circulates about these coils and flows out through the water outlet pipes 39 and 41 into the pipe 42 which empties into the first refill tank 22. The steam for the heaters is supplied from a steam main 43 connected to the power house boiler 44. Ordinarily this steam pressure will be maintained at about 55 150 pounds or as close as possible to that pressure. The condensation from the live steam heaters passes out through the traps 45 to the pipe 46 and is injected into the boiler by means of the pump 47 through the pipe 48. The valve 49 shown just 60 above the boiler may be used to cut off the supply of steam to these live steam heaters whenever steam is needed elsewhere more urgently. If desired an automatic pressure regulator cut-off valve could be substituted for the valve 49.

The power house boiler, in addition to receiving the condensation from the live steam heaters will obtain its feed water ordinarily through the pipe 51 from the storage tank 22. Since the storage 65 tank water will be maintained at temperatures ranging from 300° to 350° F. this feed water will not be much below the temperature and pressure which it must attain in the power house boiler, hence when feed water of this temperature is supplied to the power house boiler there will be very little pressure drop in the boiler and also very little time will be required for heating this water to the normal temperature and pressure of the boiler. The advantage of having this superheated feed water readily available is especially desired in connection with this system as the system is

adapted to handle the refilling of a large number of locomotives simultaneously, or at least within a short space of time such as one or two hours, and a large amount of steam must be supplied at times for holding the steam pressures in the locomotives or for giving each locomotive a final boost in temperature which will create the desired boiler operating pressure just before the locomotive rolls out of the round house. When this sudden demand for steam occurs a power house boiler connected to this system can easily supply all the steam required even though it becomes necessary to add feed water to the boiler while this high pressure steam is being withdrawn from it.

In order that the high temperature of the water may be efficiently maintained in the storage tanks 22 and 27 each of these tanks should be very well insulated as, for example, by means of a generous layer 52 of cork or asbestos or other suitable insulation.

An important advantage which results from the use of this system is found in the elimination of sludge from the water prior to the entry of the water into the locomotive boilers. Usually it is necessary to add some water softening material to the water prior to its being pumped into locomotive boilers and when the water attains high temperatures a great amount of sludge is thrown out of the water. The fast forming deposits of sludge in the bottoms of the locomotive boilers necessitate frequent blowing off of the boilers, that is, a discharging of the sludge into the atmosphere. Often this sludge must be discharged from a locomotive on the road as frequently as two or three times an hour. It is 100 apparent that this method of sludge removal causes a great loss of heated water and a loss of steam pressure. When this system, however, is used at round houses some of the sludge will be thrown down in the refill tank 13 at temperatures 105 of about 180° F. and may be removed through the sludge draw-off pipe 53. When this water from the refill tank comes into the storage tanks and becomes heated therein by contact with the previously present water the higher temperatures 110 which it then attains causes more of the sludge to be precipitated. Since the temperature of the water in the storage tanks is about the same as the temperature of the water in the locomotives it should result in the removal of most of the 115 sludge from the water while it is still in the storage tanks. This sludge can then be drawn off easily through the sludge draw-off pipes 54 and 55 which are connected to the bottoms of each 120 of these tanks.

Ordinarily in the operation of this system water is removed only from the tops of the storage tanks through the pipes 26 and 28 and is conducted only through the last mentioned pipe into the refill main 2. If by any chance the water 125 in the bottoms of the storage tanks became too cool these cooler layers of water could be conducted to the live steam heaters by opening the valve 56 and partially throttling the valve 57 so that the pump 31 would draw less water through the valve 57 and pipe 29 than it does through the valve 56 and pipes 58 and 59. In a short time this cooler water from the bottoms of both tanks could be completely heated by circulating it 130 through the live steam heaters and returning it to the storage tanks. When the above condition has been corrected the valve 56 would then be closed and the valve 57 opened wide. In the meantime the check valve 61 would have been 135 functioning to prevent any flow of this cooler 140 water. When the water in the bottoms of the storage tanks has been heated to the same temperature as the water in the top of the tanks the check valve 61 would then be closed and the valve 57 opened wide. In the meantime the check valve 61 would have been 145 functioning to prevent any flow of this cooler 150 water.

water back into the line 29 into the refill main as might otherwise happen if someone at that instant undertook to fill a locomotive boiler from the refill main.

5 Should the pump 18 fail causing a failure of supply to the storage tanks so that water could not be drawn from the tops of the storage tanks provision is made so that the water may be drawn from the bottoms of the storage tanks into the 80
10 refill mains. Other conditions than the failure of the pump might warrant drawing the water from the bottom of the refill tanks and in either event the valve 62 would be closed and the valve 63 opened. The valve 56 would also be closed 85
15 while the valve 57 would be open. Water would then flow from the bottom of the refill tanks under the pressure existing in the refill tanks into the refill main 2 and thence into any locomotives to be refilled. A by-pass 64 could then 90
20 be provided around the pump and the valve 65 therein could be opened to permit water to flow from the refill tank into the storage tank. If desired water thus taken from the bottom of the 95
25 storage tanks could be injected into the boilers by means of live steam from the steam drop. The check valves 66 provided in the steam drops are arranged to prevent water from flowing back 100
30 into the steam lines when the steam lines are connected to locomotives and would so operate should a sudden drop in the pressure of steam cause it to have a lower pressure than the superheated water already in any of the locomotive 105
boilers.

This apparatus is used to refill a locomotive in the following manner. With the valves 62 and 57 open and the valves 56 and 63 closed a hose 4 is connected to the blow-off cock of a locomotive and the valve 67 in the refill drop is opened. Upon the initial opening of this valve the superheated water will enter the lower part of the boiler and expand into steam which will quickly fill the boiler and heat it gradually, uniformly, thus preventing unequal expansion of the boiler plates. As soon as a sufficient drop in pressure occurs in the 110
45 storage tanks the governor 23 will start the pump 18 which will deliver warm water from the refill tank into the storage tanks as fast as the hottest water is drawn from the tops of these tanks. The water will continue to flow into the locomotive 115
50 boiler until a desired water level is reached at which time there will be found to exist in the boiler a steam pressure which should with proper operation of the system exceed 100 pounds. If the engine is required immediately for service the 120
55 hose 4 can be disconnected and the locomotive run out of the round house under its own power. While the boiler is being filled coal should be spread upon the grates but not ignited. The adjacent hot boiler plates should heat the coal and evaporate its moisture rendering it more easily ignitable when the locomotive gets out in the yards. If it is desired to build up pressure more rapidly in the locomotive while it is being refilled 125
60 the valve 68 in the steam drop may be opened allowing the steam and superheated water to enter simultaneously. If the locomotive is not needed at once, after it has been adequately refilled the flow of superheated water may be cut off and a high steam pressure maintained in the locomotive by opening and leaving open the steam valve 68. If the water level should gradually rise 130
65 in the locomotive and become too high the steam valve may be closed and the valve 6 in the blow-off drop opened allowing the pressure in the locomotive to blow down some of the excess water. 135

When sufficient water has then been blown down the valve 6 may be closed and the steam valve reopened. It is apparent that without changing the hose connection a working pressure may be maintained in the boiler for a considerable period of time and the water level frequently readjusted quickly and easily. Should a large number of locomotives simultaneously demand a great amount of live steam the live steam pressure may be easily maintained even though fresh feed water is required for the power house boiler, merely by pumping superheated feed water through the open valve 69 into the power house boiler. Servicing of the locomotives should therefore not interfere with the maintenance of a high steam pressure for other purposes at the locomotive terminal.

The storage tanks in any given installation will be designed to hold sufficient water to fill the maximum number of locomotives which may within any short period of time need to be refilled. One or two or more of these storage tanks may be provided as the occasion demands. The system is arranged so that the superheating of this water may be done during the hours when the 100 demands on the power house boiler are otherwise light. Accordingly a high degree of efficiency in the use of the equipment and fuel may be attained through the use of this invention.

The power house boiler will be fed during peak load hours, at least, from the storage tanks, but may be fed at other times directly from the refill tank through the connection and valve 71. The high pressure in the pipe line 51 is prevented from 105

and means for supplying the power house boiler with feed water from said storage tank.

2. In a locomotive terminal refilling system, a storage tank operatively unconnected with any firebox or the like constructed for retaining at locomotive operating pressures and corresponding temperature a quantity of water equaling the combined boiler capacities of a plurality of locomotive boilers, a power house boiler for generating high pressure steam, means for conducting water from said tank to locomotives to be refilled, means for using high pressure steam from said boiler to heat apart from the tank the water to be stored in said tank to said temperatures while under said pressures, a refilling tank adapted for storing at atmospheric pressure a quantity of water equaling the combined boiler capacities of a plurality of boilers, a blow-off main, a separator for separating steam and water blown off from locomotives and conducted to said separator by said blow-off main, a condenser for utilizing said separated steam for heating water stored in said refill tank, means for forcing water from the refill tank into the storage tank under said operating pressures and means for supplying the power house boiler with feed water from said storage tank.

3. In a locomotive terminal refilling system, a storage tank constructed for retaining at locomotive operating pressures and corresponding temperatures a quantity of water equaling the combined capacities of a plurality of locomotive boilers, a refilling main connected to said tank, a return line connected to said refill main and said tank arranged for continuous circulation of water through the tank and through the entire main, a high pressure power house boiler, means for utilizing high pressure steam from said power house boiler for heating the water flowing through said return line prior to its re-entry into said tank, and means for supplying the power house boiler with superheated high pressure water from said storage tank.

4. In a locomotive terminal refilling system, a high pressure power house boiler, a storage tank constructed to retain at locomotive operating pressures and temperatures a quantity of water equaling the combined capacities of a plurality of locomotive boilers, a refill main connected to said storage tank, a return line connected to said refill main and said storage tank arranged for continuous circulation of water from the storage tank through the entire main and back to said

storage tank, means for utilizing high pressure steam from said power house boiler for reheating to said temperatures water flowing through said return line prior to its re-entry to said storage tank, a refill tank constructed to retain at atmospheric pressure a quantity of water equaling the combined capacities of a plurality of locomotive boilers, means for heating the water in said refill tank with steam blown off from locomotives, means for supplying water from said refill tank to said storage tank at said operating pressures and mingling it with the water therein contained to heat the incoming water to the high temperatures of the storage tank prior to the time said incoming water flows from the storage tank, and means for supplying the power house boiler with superheated feed water from said storage tank.

5. In a locomotive terminal refilling system, a high pressure power house boiler, a storage tank operatively unconnected with any firebox or the like constructed to retain at locomotive operating pressures and corresponding temperatures a quantity of water equaling the combined capacities of a plurality of locomotive boilers, a refill main connected to said storage tank, a return line connected to said refill main and said storage tank arranged for continuous circulation of water from the storage tank through the entire main and back to said storage tank, means for utilizing high pressure steam from said power house boiler for reheating to said temperatures water flowing through said return line prior to its re-entry to said storage tank, a refill tank constructed to retain at atmospheric pressure a quantity of water equaling the combined capacities of a plurality of locomotive boilers, means for heating the water in said refill tank with steam blown off from locomotives, means for supplying water from said refill tank to said storage tank at locomotive operating pressures and mingling it with the water therein contained to heat the incoming water to the high temperatures of the storage tank prior to the time said incoming water flows from the storage tank, means for removing from the storage tank sludge deposited therein, and means for thermostatically controlling the return of water through said return line to said storage tank for delivering into the storage tank water heated uniformly to a desired high temperature.
